UNITED STATES PATENT OFFICE.

HARRY E. ESSIG, OF CANTON, OHIO, ASSIGNOR OF ONE-HALF TO
VICTOR A. SCHORT, OF CANTON, OHIO.

MANURE-SPREADER.

No. 824,921.

Specification of Letters Patent.

Patented July 3, 1906.

Application filed March 24, 1905. Serial No. 251,772.

To all whom it may concern:

Be it known that I, HARRY E. ESSIG, a citizen of the United States, residing at Canton, in the county of Stark and State of Ohio, 5 have invented a new and useful Manure-Spreader, of which the following is a specification.

The invention relates to a machine for unloading and distributing fertilizers or other 10 materials from the box of a wagon; and the general object of the improvement is to accomplish this result by means of construction and mechanism applied to the wagon-box, so that the same can be mounted on the 15 running-gear of an ordinary wagon and the mechanism operated by one of the wheels thereof. This object and other subsidiary ones are attained by the construction, mechanism, and arrangement illustrated in the 20 accompanying drawings, more particularly with reference to the unloading and distributing of a load of manure, in which—

Figure 1 is a sectional side elevation of a loaded wagon, showing the machine thereon, 25 with the rake-frame in operative position; Fig. 2, a plan of the wagon, showing the rake-frame lowered therein; Fig. 3, a sectional plan of the rear end of the wagon, generally on line 3 3, Fig. 1; Fig. 4, a sectional rear end 30 elevation of the wagon, on line 4 4, Fig. 1; Fig. 5, an inside elevation of the wheel-sprocket; Fig. 6, a perspective view of the wheel-sprocket bolt and washer separated; Fig. 7, a side elevation of the forward part of 35 the wagon-box; Fig. 8, a fragmentary perspective view of the left rear side of the wagon-box, showing some of the mechanism; Fig. 9, a fragmentary perspective view of the free end of the rake-frame, showing 40 the sprocket-chains without the rakes or scrapers thereon; Fig. 10, an outside elevation of the ratchet and pawl; Fig. 11 a vertical section of the ratchet and adjacent parts, on line 11 11, Fig. 10, showing the crank-handle on the shaft; Fig. 12, a detached perspective view of one-half of the clutch-sprocket-adjusting collar; Fig. 13, a fragmentary perspective view of the right rear side of the wagon-box, showing the adjustable bolster-stops; Fig. 14, an enlarged vertical section of the main shaft and adjoining and adjacent parts, on line 14 14, Fig. 2; Fig. 15, a detached perspective view of one 45 50 55 60 65 70 75 80 85 90 95 100 105 rake-frame-bearing bracket, showing the cog-

sector thereon; Fig. 16, a detached perspective view of the clutch-collar, showing the feather and its key separated therefrom; Fig. 17, a detached perspective view of one bearing-collar; Fig. 18, a detached perspective view of a scraper for unloading sand, lime, and other similar materials; and Fig. 19, a detached perspective view of a scraper with teeth for unloading wood-ashes and other similar materials; Fig. 20, a detached perspective view of the ratchet and pawl, showing the pawl held in a vertical position out of engagement with the ratchet; Fig. 21, a detached perspective view of the pawl; Fig. 22, a detached plan view of the clutch mechanism, showing the operating-bar and adjacent parts in section; and Fig. 23, a fragmentary side view of the left side-board, showing the channels and recesses therein for the operating-bar.

Similar numerals refer to similar parts throughout the drawings.

The wagon-box 1 rests on the ordinary bolsters 2 between the standards 3 of an ordinary wagon-gear, and the longitudinal bottom boards 4 on the cross-sills 5 are preferably located with a slight interval between them to provide for lateral expansion. The side-boards 6 are preferably stayed on the outside by the braces 7, attached on the outer projecting ends of the cross-sills. The side-boards extend a short distance to the rear beyond the ends of the bottom boards, and on these projecting ends are attached the main bearings 8 for the transversely-located main shaft 9 of the machine.

The rake-frame is pivotally mounted concentric with the main shaft, preferably by means of the bearing-brackets 10, journaled on the hubs 11 of the main bearings, and the bearing-collars 12 are provided on the shaft and preferably shield the ends of the abutting bearings from dirt or grit. The rake-frame is preferably composed of the side bars 13, attached to the bearing-brackets, the forward, middle, and rear cross-bars 14, 14^a, and 14^b, the intermediate cross-bars 14^c and 14^d, the cross-tie rod 15 and 15^a at the forward end and middle, the diagonal brace-rods 16, from the middle to the rear end, and the longitudinal bearing-strips 13^a, attached at intervals apart on the under sides of the cross-bars. The side bars and the bearing-strips are preferably tapered in width, so that the

free end of the frame is lighter than the base end.

The main sprockets 17 are securely mounted at intervals apart on the main shaft, and the corresponding idle sprockets 19 are mounted in suitable bearings formed in the brackets 20, attached to the forward cross-bar of the frame, and the sprocket-chains 21 operate on these respective sets of wheels, a suitable 5 tightener, as 22, being preferably provided on the middle cross-bar for each chain. The scrapers, preferably the rakes 23, having the tangs 24 projecting outward, are transversely attached at intervals on the outer sides of the 10 sprocket-chains, and these rakes are preferably staggered in location, so that the rakes of one chain will be opposite the intervals between the rakes of the adjacent chain, and the sprocket-wheels and chains are preferably 15 so separated that the ends of the rakes will not overlap, but will bring the lines of travel of the adjacent end tangs somewhat closer together than are the tangs of the respective rakes. The chains are also alined 20 with the bearing-strips, so that these strips constitute a stay or support against which the chains and rakes abut in the operation of 25 the machine.

The shield or hood 25 is attached on the 30 free end of the rake-frame to protect the driver from being caught by the sprocket-wheels and rakes and to keep the idle sprockets clean, and the feet 26 are provided at this end to hold the frame up, so that the 35 rakes will not rest or drag too much on the bottom boards of the box. The cylindric shields or drums 27 are provided around the main shaft between the sprocket-wheels and are preferably of about the same diameter as 40 the rims of the wheels, which prevent straw or other refuse from engaging or wrapping around the rotatable parts, and the brushes 28 are attached on the adjustable transverse bar 29, back of the main sprocket-wheels 45 and serve to remove adhering material from the wheels and chains.

The crank-shaft 30 is mounted in the bearings 31 and 31^a at the rear end of the box, preferably horizontal and to the rear and below the main shaft. The cog-pinions 32 are securely mounted on this shaft, preferably inside of and adjacent to the side boards, and the crank 33, with the handle 34, is securely mounted on the projecting end of this shaft, preferably 55 on the right side of the wagon-box. The cog-sectors 35 are formed or attached on the rear ends of the bearing-brackets 10 and are adapted to mesh with the cog-pinions on the crank-shaft, so that by rotating 60 the crank the forward end of the rake-frame is raised or lowered, being rocked on its pivotal bearings by means of the intermeshing cog pinions and sectors. The ratchet-wheel 36 is securely mounted on the crank-shaft, 65 preferably between the crank and the adja-

cent bearing, and one half or side of its periphery is provided with the ordinary inclined faced or acute-angled teeth 37, while the other half or side is provided with the square-shouldered recesses 38. The pawl 39 is pivotally attached, preferably on the plate 40 of the bearing 31, and one side of the pawl is provided with the acute-angled detent 41, which is adapted to engage with the acute-angled teeth of the ratchet, while the other side of the pawl is provided with the square detent 42, which is adapted to engage in the square-shouldered recesses of the ratchet, according as the pawl is thrown one way or the other. The flat-faced lugs 43, having inclined sides 44, are provided on the end of the pawl-hub 45, against which the ends of the bow-spring 46, securely attached on the pawl bearing 47, are adapted to operate, by means of which the pawl is releasably held in a vertical position out of engagement with the ratchet-wheel, when the rake-frame is being raised. The crank-handle is loosely mounted on its shaft and is free to move endwise thereon between the hub 48 of the ratchet-wheel and the stop-pin 49, and the contiguous ends of the crank and ratchet-hubs are provided with the engaging inclined-faced square-shouldered teeth 50 arranged to free the crank from rotation when the rake-frame 95 is being lowered in the operation of the machine.

The wheel-sprocket 51 is attached, preferably, on the inside to the left rear wheel of the wagon, and a convenient way of making this 100 attachment is by the bolts 52, passed through the slots 53 in the web 54 of the wheel-sprocket and having their free ends 55 curved or crooked to engage around the spokes 56 of the wheel with the intervening 105 notched washer 57. The clutch-sprocket 58 is rotatably mounted on the projecting end of the main shaft in alinement with the wheel-sprocket and is preferably held in position by means of the adjusting-collar 59, 110 clamped on the shaft on the outer side of the sprocket, which collar is provided with the internal annular flange 60, adapted to engage and operate in the external annular groove 61, formed in the hub of the sprocket, 115 by means of which collar the sprocket can be readily adjusted endwise along the shaft to bring it into alinement with the wheel-sprocket. The clutch-collar 62 is feathered on the shaft inside the clutch-sprocket, and the contiguous ends of the collar and sprocket are provided with the engaging square-shouldered inclined-faced teeth 63. The feather 64 is attached in the groove 65 in the clutch-collar by the key 66, passed 125 through the apertures 67 in the lugs 68 outside of the lug 69 on the end of the feather, so that the feather goes and comes with the collar and travels in the shaft-channel 70, which arrangement is necessary to permit the 130

clutch - sprocket to be adjusted along the shaft for use in wagons of different widths. The minor bearing 71 for the main shaft is attached on the outer side of the left side-board, preferably by the plate 72 and the bolts 73, and the clutch-bracket 74 is preferably attached by means of its plate 75, abutting against the bearing-plate and secured by the same bolts. The outer bearing 76 is formed on the clutch-bracket, by means of which minor and outer-bearings the projecting end of the main shaft is firmly supported and sustained, and it is evident that the parts of the clutch can be readily removed for cleaning and repairs by merely removing the clutch-bracket and without disturbing the main shaft. The flange 77 is provided on the minor bearing adjacent to its plate, and the clutch-bolt 78 is arranged to operate endwise in suitable apertures 79 in the flange and plate. The coil-spring 80 is provided around the bolt between the bearing-plate and the stop or pin 81 on the bolt, which spring acts to throw the bolt endwise outward, and on the free outer end of the bolt is provided the adjustable yoke 82, which is adapted to operate in the annular groove 83 of the clutch-collar, whereby the spring acts to hold the collar in engagement with the clutch-sprocket. The inner end of the clutch-bolt is bent upward to form the shoulder 84, which is adapted to operate in the recess 85 in the side-board of the box, and the longitudinal channel 86 is provided in the side-board and extends from this recess to the forward end of the side-board, in which recess the operating-bar 87 is located and is adapted to move endwise without interfering with or being restrained by the bolstered standards. The operating-lever 88 is pivoted to the forward end of the side-board and is provided with the slot 89, in which the wrist-pin 90 on the forward end of the operating-bar is adapted to operate. The rear part 91 of the operating-bar is thickened on the inside to form the wedge-face 92, and in the rear end of this face is provided the notch 93. The channel 94 is provided in the side-board to accommodate the movement of the wedge end of the operating-bar. The shoulder 84 on the inner end of the clutch-bolt is held by action of the spiral spring against the inner side of the operating-bar when the clutch-collar and sprocket are in engagement, and when it is desired to throw the clutch out of engagement the operating-rod is drawn forward by action of the driver's foot on the operating-lever, and the rear wedge end of the bar is drawn between the bolt-shoulder and the minor bearing-plate and forces the bolt inward to disengage the clutch, and when the shoulder enters the notch at the end of the bar it serves to lock the clutch in its open relation until the operating-bar is positively thrust

backward. The operating sprocket-chain 95 is provided for the wheel and clutch sprockets, by means of which power is transmitted from the wagon-wheel to the unloading mechanism.

When the wagon is empty, the clutch is thrown out of engagement and the feet at the free end of the rake-frame normally rest on the bottom of the box, as shown by broken lines in Fig. 1, and when it is desired to load the wagon the pawl is thrown up out of engagement with the ratchet, and by rotation of the crank the frame is raised to or near the vertical position, as shown by dotted lines in Fig. 1, whereupon the square detent 80 of the pawl is thrown into a square-shouldered recess of the ratchet-wheel, which prevents a movement of the rake-frame either forward or backward, in which position the load 96 may be placed on the wagon without any danger of the frame falling either way by reason of a sudden movement thereof. When the wagon is loaded, the pawl is thrown so that its acute-angled detent is in engagement with the acute-angled teeth of the ratchet-wheel, and the rake-frame is lowered by means of the crank until it rests against the rear end of the load, as shown by full lines in Fig. 1. In this relation the pawl permits the frame to be freely lowered, but prevents a reverse movement of the same, and thus saves the frame from being thrown backward by a sudden forward movement of the wagon. The wagon is now hauled from the barnyard to the field, and when the place of distribution is reached the clutch is thrown into engagement, and by the operation of the machine the rakes are drawn downward and rearward between the manure and the bearing-strips, and comb and cut through and pulverize the manure and carry the particles thereof to the rear end of the wagon, from which they are discharged and distributed in an even manner through the throat between the shaft-shield and the adjacent rear ends of the bottom boards. The width of this throat is regulated by the adjustable extension 97, attached on the rear ends of the bottom boards of the box. The weight of the frame by the bearing of its strips against the inner sides of the sprocket-chains impresses the rakes in engaging contact with the manure, and as the load is reduced the rake-frame follows it downward by its own weight until the wagon-box is empty, the frame being made of such size as to substantially cover the bottom of the wagon-box when it is lowered therein. Scrapers formed as shown in Fig. 18 are preferably used on the sprocket-chains for unloading and distributing dry-slaked lime, sand, or other powdered or granular materials, and scrapers formed with teeth, as shown in Fig. 19, are preferably used for wood-ashes and other materials which are apt to pack in bulk. The wheel-

sprocket is preferably centered on the wagon-wheel by means of the radial adjusting-screws 98, passed through the lugs 99 on the web of the sprocket and adapted to abut against the hub of the wheel, and the wagon-box is firmly held in proper longitudinal position on the wagon-gear by means of the adjustable stops 100, arranged to abut on each side of preferably the rear bolster, and by adjustment of these stops the operating sprocket-chain can be kept taut without other tightening devices.

It is evident that the unloading mechanism herein illustrated and described can perform its work with the application of very little power, because the load is removed by raking or scraping small portions from the top thereof. Furthermore, as the load does not rest upon any part of the mechanism there is no limit to the weight or quantity of the load which can be removed by the mechanism excepting only the strength and capacity of the wagon and its box.

What I claim as my invention, and desire to secure by Letters Patent, is—

1. In a wagon-box, a rocking frame fulcrumed thereon and arranged to rest on the load and being free to follow it downward, with means for stopping the frame from moving upward, chains having scrapers thereon and arranged to operate around the frame and operative connections between the chains and a wheel of the wagon.

2. In a wagon-box, a movable frame mounted thereon and arranged to rest on the load and being free to follow it downward, with means for stopping the frame from moving upward, chains having scrapers thereon and arranged to operate around the frame and operative connections between the chains and a wheel of the wagon.

3. In a wagon, a rocking frame fulcrumed on the box and normally resting therein, strips on the under side of the frame, chains having scrapers thereon and arranged to operate around the frame and to bear longitudinally against the strips, and operative connections between the chains and a wheel of the wagon.

4. In a wagon, a movable frame mounted on the box and normally resting therein, strips on the under side of the frame, chains having scrapers thereon and arranged to operate around the frame and to bear longitudi-

nally against the strips, and operative connections between the chains and a wheel of the wagon.

5. In a wagon mechanism, a rocking frame, a shaft having operative connections with the frame, a ratchet on the shaft having inclined faced teeth on one side and square recesses in the other side of its periphery, and a pawl having an acute-angled detent on one side adapted to engage the inclined faced teeth and a square detent on the other side adapted to enter the square recesses of the ratchet.

6. In a wagon mechanism, a rocking frame, a horizontal shaft having operative connections with the frame, a hub fixed on the shaft, and an adjacent crank having a hub movably mounted on the shaft, the contiguous ends of the hubs having engaging inclined-faced square-shouldered teeth.

7. In a wagon mechanism, a rocking frame, a shaft having operative connections with the frame and a clutch-collar feathered thereon, an adjacent bearing-plate having a spring-resisted bolt mounted therein operatively connected with the collar at one end and having a shoulder at the other end, and an end-wise - movable operating - bar between the plate and the shoulder having a wedge-shaped end thereon with a notch at the end adapted to receive the shoulder.

8. In a wagon mechanism, a rocking frame, a shaft having operative connections with the frame and a clutch-collar feathered thereon, an adjacent bearing-plate having a spring-resisted bolt mounted therein operatively connected with the collar at one end and having a shoulder at the other end, and an end-wise - movable operating - bar between the plate and the shoulder having a wedge-shaped end thereon.

9. In a wagon-unloading mechanism, a rocking frame having sprockets on the ends thereof, and a hood on the free end of the frame arranged to shield the sprockets thus located.

In testimony whereof I have signed my name to this specification in the presence of two subscribing witnesses.

HARRY E. ESSIG.
